UNITED STATES PATENT OFFICE

168,221

LOUVER UNIT

Renato J. Gonnella, Miami, Fla.

Application June 9, 1950, Serial No. 10,438

Term of patent 14 years

(Cl. D13—1)

To all whom it may concern:

Be it known that I, Renato J. Gonnella, a citizen of the United States, residing at Miami, in the county of Dade and State of Florida, have invented a new, original, and ornamental Design for Louver Unit, of which the following is a specification, reference being had to the accompanying drawing, forming a part hereof.

Figure 1 is a front perspective view of a louver unit showing my new design; and

Figure 2 is an exploded view thereof.

I claim:

The ornamental design for a louver unit, substantially as shown.

RENAUTO J. GONNELLA.
